US00D768619S

(12) **United States Design Patent** (10) **Patent No.:** **US D768,619 S**
(45) **Date of Patent:** **** Oct. 11, 2016**

(54) **DISPLAY**

(71) Applicant: **Apple Inc.**, Cupertino, CA (US)
(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US); **Kevin Robinson**, Cupertino, CA (US); **Houtan Farahani**, San Ramon, CA (US); **Wey-Jiun Lin**, Los Altos, CA (US); **Bryan William Posner**, La Selva Beach, CA (US)

(73) Assignee: **Apple Inc.**, Cupertino, CA (US)

(**) Term: **14 Years**

(21) Appl. No.: **29/519,707**

(22) Filed: **Mar. 6, 2015**

(51) **LOC (10) Cl.** **14-02**

(52) **U.S. Cl.**

(57) **CLAIM**

The ornamental design for a display, as shown and described.

DESCRIPTION

FIG. 1 is a front view of a display showing our new design;
FIG. 2 is a rear view thereof;
FIG. 3 is a left side view thereof;
FIG. 4 is a right side view thereof;
FIG. 5 is a top view thereof; and,
FIG. 6 is a bottom view thereof.

The dashed broken lines represent structure or features which form no part of the claimed design.

The oblique shade lines represent a transparent, reflective, or glossy surface.

1 Claim, 6 Drawing Sheets
